DECORATIVE LABEL-TYPE EMBLEM

Louis Wimberly, P.O. Box 1, Litchfield, Ill. 60538

Filed Aug. 13, 1973, Ser. No. 388,159

Term of patent 14 years

Int. Cl. D19—08

U.S. Cl. D19—13

The figure is a plan view of a decorative label-type emblem, showing my new design.

The claimed design is of no substantial thickness.

I claim:

The ornamental design for a decorative label-type emblem, as shown and described.
